M. D. DREYFUS.
STONE GIRDLING TOOL.
APPLICATION FILED JAN. 25, 1917.

1,244,716.

Patented Oct. 30, 1917.

UNITED STATES PATENT OFFICE.

MAX D. DREYFUS, OF NEW YORK, N. Y.

STONE-GIRDLING TOOL.

1,244,716.

Specification of Letters Patent. Patented Oct. 30, 1917.

Application filed January 25, 1917. Serial No. 144,859.

To all whom it may concern:

Be it known that I, MAX D. DREYFUS, a citizen of the United States of America, residing at New York city, county and State of New York, have invented certain new and useful Improvements in Stone-Girdling Tools, of which the following is a full, clear, and exact description.

This invention relates to improvements in cutting-tools and has for an object to provide an efficient and inexpensive tool arranged to accurately girdle precious stones, especially diamonds. The girdling of diamonds has heretofore been accomplished by hand-grinding, and the object of my invention is, as has been stated, to provide a tool to girdle or trim the peripheral edge of a stone by mechanical means whereby a great amount of time is saved and a more accurate circle is produced. My improved tool may, of course, also be utilized for other purposes.

I will now proceed to describe my invention in detail, the novel features of which I will point out in the appended claims, reference being had to the accompanying drawing, forming part hereof, wherein:

Figure 1 is a face view of my improved cutting tool illustrated as connected to a drill-chuck;

Fig. 2 is an enlarged cross-sectional view, the section being taken on a line 2—2 in Fig. 1;

Fig. 3 is a similar view, the section being on a line 3—3 in said Fig. 1;

Fig. 4 is an enlarged vertical sectional view, the section being taken on a line 4—4 in Fig. 1;

Fig. 5 is a perspective view of a modified form of my cutting tool;

Fig. 6 is an enlarged sectional plan view, illustrating a cutting tool positioned to cut the ragged or rough edge of stones encompassed thereby;

Fig. 7 is a sectional view of a modified form of means to lock the adjusting spindle;

Fig. 8 is a sectional view illustrating the action of the grinders; and

Fig. 9 is a perspective view of another form of circular grinder.

As herein embodied, my invention comprises a frame or holder 1 carrying cross-bars 2 and 3 which slidably retain the posts 4 and 5 which carry the grinding tools 6 and 7. These tools are made of suitable hard metal, the grinding edges of which are pro-

vided with well-known diamond grinding compositions, such as diamond-dust or the like, the manner of forming such grinding edges being well-known in the art. Each post 4 and 5 carries a block 8 to which its respective grinder is detachably secured by bolts 9. The upper end of each post 4 and 5 carries a threaded projection 10 which is engaged by a jam or lock-nut 11. To adjust the posts 4 and 5, and consequently the grinders 6 and 7, I provide a rotatable spindle 12 carrying a thumb wheel 13. The spindle 12 is oppositely threaded as shown, the right-hand threaded portion engaging a threaded opening in the hub 14 of the post 4. The left-hand threaded portion of the spindle 12 engages the hub 14 of the post 5. When the spindle is rotated, the grinders 6 and 7 will be adjusted toward or away from each other according to the direction of rotation. When adjusted the posts 4 and 5 and their grinders will be locked in the adjusted position by the lock-nuts 11. To permit the posts to be adjusted longitudinally of the holder 1, or cross-bars 2 and 3, I provide said cross-bars with slots 15 and 16, respectively, through which the said posts pass. The grinders consist of the shanks 6^a and 7^a and the semi-cylindrical or cage grinding portions or members 15^a and 16^a carried thereby. The shanks 6^a and 7^a are formed preferably integral with the semi-cylindrical portions 15^a and 16^a, respectively. Each portion 15^a and 16^a is provided with a grinding edge 17 to trim or true up the rough peripheral edge of a gem 19 (Fig. 8). The semi-cylindrical or cage portions, when arranged or adjusted for the gem which they are to trim or true up, act as a centering device for the gem; in other words, the gem to be tried or ground will lay within the circle formed by the two semi-cylindrical cage-portions of the grinders. Hence, the gem will not be lashed out of position to any harmful extent while the grinding edges are performing their function.

Instead of the semi-cylindrical cages and their grinding edges, I may employ, for some classes of work, straight grinders, indicated by 20 in Fig. 5, the grinding edge thereof being indicated by 21.

For soft stones or metal (indicated by 19^a, Fig. 6) cutters such as 6^b and 7^b can be employed, having inturned grinding or cutting

edges 17^a; said cutters being carried by the posts 6^a and 7^a.

Instead of employing the jam-nuts 11, on the posts 4 and 5, I may mount a lock-nut 22 directly upon the spindle 12, as illustrated in Fig. 7. For stones of different sizes or diameters, I employ grinders 6 and 7 having semi-cylindrical cages of suitable radius. To accommodate stones of different diameters, the posts 4 and 5 will be adjusted along the holder. When an adjustment is made, grinders of suitable size will have to be applied to the posts 4 and 5.

The holder 1 will be applied to a chuck 23 of a drill, or the like, and, while rotating, will be fed against the edge of the stone to be trued up; hence the girdle edge of the stone will be ground to an exact circle or approximately so. A stone trued by my improved device will be more perfectly formed, at less cost, than could be accomplished by hand. If desirable micrometer scale indications 24 can be applied to the holder 1 adjacent the adjustable posts 4 and 5.

To girdle a diamond or other hard stones, I may employ a one-piece grinding tool indicated by 25, Fig. 9, which can be held by the posts 4 and 5. To attach the grinder 25, the posts will be moved apart or moved together, to engage the shanks 26 of the grinder 25. This form of grinder is desirable for hard stones, as there will be no tendency to spread while being fed against the stone. The edge 27 of the grinder 25 will be the grinding edge, the cutting or grinding edges of these tools being made of well known diamond grinding compositions.

Having now described my invention, what I claim and desire to secure by Letters Patent is:

1. A grinding tool comprising a holder, a plurality of grinders adjustably carried thereby, each grinder consisting of a semi-cylindrical cage-portion, and a grinding edge carried by each cage-portion.

2. A grinding tool comprising a holder, a spindle rotatably supported thereby and provided with right and left hand threads, a slideable post engaging the left-hand threads of the spindle, a second post engaging the right-hand threads of said spindle, means to rotate said spindle, means to lock the posts in

adjusted positions, and grinders removably secured to said posts.

3. A grinding tool consisting of a holder, 55 cross-bars carried thereby and provided with slots, posts slidably engaging said slots, means to slide said posts in said slots, means to lock said posts when moved to a desired position, and grinders carried by said posts. 60

4. A grinding tool, consisting of a holder-frame, a pair of cross-bars carried thereby and provided with slots, posts passing through and slidably engaging said slots, a threaded spindle engaging said posts, means 65 to rotate said spindle, and grinders carried by said posts.

5. A grinding tool, consisting of a holder, cross-bars carried thereby and provided with slots, posts slidably engaging said slots, 70 a threaded spindle engaging said posts, means to rotate said spindle, grinders carried by said posts, and means to lock said spindle against rotation at will.

6. A grinding tool, consisting of a holder, 75 cross-bars carried thereby and provided with slots, posts slidably engaging said slots, a threaded spindle engaging said posts, means to rotate said spindle, grinders carried by said posts, a threaded projection carried by each post, and a jam-nut carried by each projection to bear against the adjacent cross-bar and lock said posts against movement after said posts have been adjusted. 80

7. A grinding tool, comprising a holder-frame, a rotatable threaded spindle carried thereby, grinders adjustably connected to said spindle, and a jam-nut to lock said spindle against rotation. 85

8. A grinding tool for precious stones, 90 consisting of a curved cage having a grinding edge at the lower end thereof, and shanks extending from said cage adapted to engage a rotatable support.

9. A grinding tool for precious stones, 95 comprising a plurality of curved cages arranged to form a circle, each cage having a grinding edge at the lower end thereof.

Signed at New York city, N. Y., this 24 day of January, 1917.

MAX D. DREYFUS.
